LADY'S STOCKING

William G. Bley, Richboro, Pa., assignor of one-half to Richard M. Spurgeon, Philadelphia, Pa.

Filed Apr. 15, 1960, Ser. No. 60,210

Term of patent 14 years

(Cl. D47—7)

Fig. 1 is a front perspective view of a stocking showing my new design;

Fig. 2 is a rear perspective view thereof; and

Fig. 3 is a side elevational view of the same stocking in partially folded condition.

I claim:

The ornamental design for a lady's stocking, as shown.
